his Attorney

UNITED STATES PATENT OFFICE.

ERWIN C. BAUMGRAS, OF WASHINGTON, DISTRICT OF COLUMBIA.

DESIGN FOR A SPOON.

SPECIFICATION forming part of Design No. 20,665, dated April 7, 1891.

Application filed March 14, 1891. Serial No. 385,133. Term of patent 3½ years.

To all whom it may concern:

Be it known that I, ERWIN C. BAUMGRAS, a citizen of the United States, residing at the city of Washington, in the District of Columbia, have invented and produced a new and original Design for a National Souvenir Spoon, of which the following is a specification, reference being had to the accompanying drawing, forming a part thereof.

The leading features of my design consist, first, in the handle, which has thereon a representation of the Goddess of Liberty standing on the apex of a temple, said temple showing a series of vertical columns resting on a base. Below this base is a heraldic shield, on which is displayed the coat of arms of the United States. Above the head of the God-

dess of Liberty is a short extension or vertical post, over which is a crossed band, upon which stars are displayed. A similar band, with stars thereon, extends transversely across the upper end of the post, said band being on the line of connection of the handle with the bowl. Upon the inner surface of the bowl is a perspective view of a section of the rotunda of the Capitol of the United States.

What I claim is—

The design for a spoon herein described, and illustrated in the drawing.

ERWIN C. BAUMGRAS.
